United States Patent Office.

FRANCIS CLYMER, OF GALION, OHIO.

Letters Patent No. 87,636, dated March 9, 1869; antedated March 5, 1869.

IMPROVED CLOTHES-LINE FASTENER.

The Schedule referred to in these Letters Patent and making part of the same.

To all whom it may concern:

Be it known that I, FRANCIS CLYMER, of Galion, county of Crawford, and State of Ohio, have invented certain new and useful Improvements in Clothes-Line Fasteners; and I do hereby declare that the following is a full, clear, and exact description of the same, reference being had to the accompanying drawing, and the letters of reference marked thereon, making part of this specification, in which—

Figure 1 is a side view of a post or pole with my device attached.

Figure 2 is a front view of the same.

Figure 3 is a side view of the cam detached, showing the ratchet-teeth and flange.

Figure 4 is an inner face view of fig. 3.

Figure 5 is a view of the pin detached.

Figure 6 is a face and side view of the pivot-screw, with its wrench or crank-arm.

The nature of my invention consists in providing a post, or pole, such, for instance, as is generally used for clothes-lines, or for attaching the tie-line of horses to, that the device by which the line is retained can be rendered adjustable thereon, thus permitting the same pole to be advantageously used for supporting lines or cords of different heights.

The devices by which the cord are retained are of the most simple character, and consist of a cam, provided with ratchet-teeth, and a flange, so arranged, in combination with a grooved bearing-pin, that the teeth engage with the rope, thus securely preventing the same from giving, in a forward direction, while, by the flange entering the groove in the pin, all danger of the same slipping in a lateral direction is securely and entirely guarded against.

To enable others skilled in the art to make and use my invention, I will now proceed to describe its construction and operation.

A is an ordinary wooden post, or pole, and may be either square, round, or octagonal in form.

This pole A is provided with a series of holes, *a* and *a'*. While the distance between each set of holes *a* and *a'* must invariably be the same, the distance between the different sets may vary, and thus enable me to increase the degree of adjustability at pleasure.

B is a cam-plate, and is constructed in the form shown in the drawings, its lower surface, *b*, being a section of a circle, or nearly so.

This plate may be made of any suitable metal, and is cast with an inner plate, provided with teeth *b'*, its lower surface, *b*, acting as a flange.

This plate B is pivoted, by means of a bolt, C, provided with a wrench, or crank-arm, in one of the holes *a*.

D is an ordinary bearing-pin, and may be made of either wood or metal, and is provided with a slot, *d*, and tenoned, as shown at *d'*, fig. 5, so as to fit in one of the holes *a'*.

There may be several slots in the pin, whereby the device can readily be made to accommodate itself to ropes of different thicknesses.

From this description, the operation will readily be understood.

The cam having been swung to one side, the rope is placed on the pin C. When the desired tension has been given, the cam is allowed or caused to fall on the rope. The tread of the inner plate *b'* will be immediately on the rope, its teeth engaging therewith, while the flange, entering the groove or slot *d*, renders it impossible for the rope to slide off the pin D. Thus it will be seen that when the strain is greatest, the rope is most tightly held.

A peculiar advantage of my invention consists in its entire adjustability. Suppose the device to be in the position shown at *x*, figs. 1 and 2, and it should become desirable to elevate the same. Simply by turning the wrench and crank-arm *b*, the screw will be released, when, by inserting it in the hole *a* above, you will have the cam attached in the position shown in red. Then, by withdrawing the pin C, and inserting it in the hole *a'* above, the height of the fastener is entirely changed.

Thus, it will be observed, by simply constructing the pole or post A with several sets of these holes *a* and *a'*, how completely and entirely the fastener can be rendered adjustable.

Having thus fully described my invention,

What I claim therein as new, and desire to secure by Letters Patent of the United States, is—

The cam B, toothed plate *b'*, and flange *b*, when cast in one piece, and made readily adjustable by means of the wrench-screw C and grooved pivot D, inserted in the hole of the post.

In testimony whereof, I have signed my name to this specification, in the presence of two subscribing witnesses.

F. CLYMER.
